UNITED STATES PATENT OFFICE

ARTHUR ATWATER KENT, OF ARDMORE, PENNSYLVANIA

DESIGN FOR A CABINET FOR RADIO RECEIVING APPARATUS

Application filed May 26, 1930. Serial No. 35,764. Term of patent 7 years.

To all whom it may concern:

Be it known that I, ARTHUR ATWATER KENT, a citizen of the United States, residing at Ardmore, county of Montgomery, State of Pennsylvania, have invented a new, original, and ornamental Design for a Cabinet for Radio Receiving Apparatus, of which the following is a specification, reference being had to the accompanying drawing, forming part hereof.

The figure is a perspective view of a cabinet for radio receiving apparatus, showing my new design. The front of the cabinet according to my new design primarily comprises, in combination, legs having balls and rings adjacent the upper ends, a transverse scroll apron at the base of the cabinet, a central panel and side panels rising directly from

the scroll apron and extending to the top of the cabinet, the side panels across the top having relatively wide bands provided with vertical ribs and grooves, the central panel being inset and having an arch extending above the lower extremities of said bands and also having a transverse band narrower and materially lower than said bands and provided with vertical ribs and grooves and ornamental beading on the side panels extending above the lower edge of said band of the central panel.

I claim:

The ornamental design for a cabinet for radio receiving apparatus, as shown and described.

ARTHUR ATWATER KENT.
